THROTTLE VALVE

William A. Strauss, 712 Marburn Drive, Columbus, Ohio
Filed Dec. 22, 1961, Ser. No. 161,715
8 Claims. (Cl. 137—625.3)

This invention relates to fluid throttling valves and more particularly to a valve means adapted to throttle the volumetric flow rate of liquids in a substantially linear manner with respect to the movement of a valve actuator.

In the metering of liquids and gases, for example, it is frequently necessary to precisely vary the flow rate in a linear manner through a range that extends from a positive shut-off position to a full flow position. In general, the apparatus of the present invention provides both linear flow rate control and positive shut-off by means of improved flow control devices of the type that incorporate a porous element in moveable confronting relationship with an impervious wall surface whereby movement of an actuator progressively and linearly increases or decreases the area of the porous element exposed to the pressure differential of the fluid.

More specifically, the valve means of the present invention comprises an actuator means that not only meters the fluid flow in a linear manner, but also functions in combination with the housing means of the valve to form a positive shut-off for the valve.

It is, therefore, an object of the present invention to provide an improved throttle valve adapted to linearly vary the volumetric flow of a fluid from a positive shut-off position to a full flow position.

Other objects and advantages of the present invention will be apparent from the following description, reference being had to the accompanying drawings wherein preferred forms of embodiments of the invention are clearly shown.

In the drawings:

FIG. 1 is a partial side sectional view of a throttle valve constructed in accordance with the present invention, the section being taken along a vertical plane through the center line of the device;

FIG. 2 is a second partial side sectional view of a modified throttle valve constructed in accordance with the present invention, the section being taken along a vertical plane through the center line of the device; and

FIG. 3 is a third partial side sectional view of a modified throttle valve constructed in accordance with the present invention, the section being taken along a vertical plane through the center line of the device.

Referring in detail to the drawing, FIG. 1 illustrates a throttle valve that includes a porous element 80 slideably mounted in a bore 90 formed in the cup-shaped portion 72 of housing means indicated generally at 60.

With continued reference to FIG. 2, the top end of porous element 80 is rigidly secured to the lower end 76 of an actuator means 62, the latter being slideable mounted in a bore 61 through top closure 64 and extended into a chamber 74 formed by cylindrical inner housing surface 78.

An inlet port 78 communicates with chamber 74 and the porous outer side surface 75 of element 80.

Top closure 64 includes a resilient shaft seal 66 and a resilient housing seal 70.

As seen in FIG. 2, the lower end of porous element 80 is covered by an impervious washer 86 which is rigidly attached to the porous element 80 by welding, cementing, or other suitable attaching means.

The outer porous side surface 75 of the porous element 80, FIG. 1, is engaged by an annular resilient seal 82 in the annular wall of bore 90 and 86 includes a similar seal 88 that prevents the rapid flow of fluid between the outer

2

surface 75 of the porous element and the inner surface of bore 90.

A port 92 is provided for the inlet or outlet of the flowing fluid controlled by the valve.

5 The porous element 80 may include bore 84 having any dimension including zero.

Referring next to the modification of FIG. 2, a cup-shaped housing portion 106 and top closure 104 form a housing means indicated generally at 100. An actuator means 102 is attached to a cup-shaped end portion 116 at a welded junction 103 in slideable engagement with the inner surface 108 of housing portion 106, an annular resilient seal 112 being provided between the confronting surfaces.

15 In the embodiment of FIG. 2 a porous element 114 is secured at its lower end to the top surface of a threaded impervious washer 124 that includes an outer surface 123 that forms a shut-off portion. When actuator 102 is moved downwardly, an annular seal 118 at the inner surface 110 of the cup-shaped actuator portion 116 form a shut-off valve portion that moves into seal surrounding relationship with the shut-off valve portion 123 formed by the outer surface of a washer 124 mounted in the lower end of the housing means at a threaded junction 130.

20 With continued reference to FIG. 2, one of the ports 132 in the housing means communicates with the other of the ports 128 via bore 120, the annular wall of porous element 114, and chamber of 122.

25 Reference is next made to FIG. 3 which illustrates still another modified throttle valve constructed in accordance with the present invention that includes a housing means indicated generally at 140 and provided with a lower casing portion 142, a top closure 144, a threaded bore 172, and ports 154 and 176.

30 In the embodiment of FIG. 3 a porous element 158 is provided with a bore 162 and threads 160 in threaded engagement with the threaded inner surface of bore 172.

35 In the embodiment of FIG. 3 the upper end of porous element 158 is rigidly attached to the lower threaded end 156 of an actuator means 143, the latter being freely extended through a bore 141 in top closure 144.

40 The lower end of porous element 158 is sealed by a rigidly attached impervious washer 164 that includes a bore 166 and an outer threaded surface 168 in engagement with the threaded inner surface of bore 172.

45 In the embodiment of FIG. 3 the positive shut-off occurs when the lower annular end portion 180 of actuator means 143 and a resilient seal 152 carried thereon are moved downwardly into an annular recess 170 in the housing means wherein the annular resilient seal 152 engages the inner surface 182 of recess 170.

50 The fluid flow between the ports 154 and 176, FIG. 3, occurs via bores 174 and 172, a hole 166 through impervious washer 164, and the annular wall of porous element 158.

55 The engagement of threads 168 on impervious washer 164 and threads 160 on porous element 158 with threads in bore 172 comprise an integral actuating means.

60 The porous element 158, FIG. 3, may include bore 162 of any dimension including zero.

65 In the various figures, elements 36, 50, 126, 143, 148, and 150 obviously constitute O-ring seals not specifically mentioned in describing the figures. It will be understood that these seals and the others specifically mentioned can be modified in type and form without departing from the spirit of the invention.

70 In operation it should be pointed out that the volumetric rate of fluid flow through any of the porous elements illustrated is directly proportional to

75 (1) The surface area of the porous material exposed to the pressure differential

- (2) The porosity of the restrictor
 (3) The pressure differential

and inversely proportional to

- (1) The length of porous material through which the fluid must pass.

The fluid flow is, therefore, throttled by varying either the exposed surface area, the length of the restrictor or the porosity of the restrictor. To control larger volume flows, large surface areas of high porosity material can be employed. For smaller volume flows, low porosity restrictors and long flow paths through the restrictor can be used. Direct control of these parameters may be made in many ways, several of which are illustrated in the accompanying drawings. Each of these various embodiments provides an actuator means housing means and porous element that are combined in unique structural arrangements so as to provide both linear control of the fluid flow and positive shut-off at the low end of the flow control range.

While the forms of embodiments of the present invention as herein disclosed constitute preferred forms, it is to be understood that other forms might be adopted, all coming within the scope of the claims which follow.

I claim:

1. A metering valve comprising, in combination, housing means forming a chamber including an inner wall surface, an inlet port and an outlet port; actuator means moveably mounted in said housing and including an actuator wall surface; a porous element forming passage means connecting said two ports, said porous element and one of said wall surfaces being in relative slideable engagement with one another; a first shut-off valve portion on one of said means; a second shut-off valve portion on the other of said means, one of said valve portions being moveable through a flow metering range and into sealed engagement with the other of said valve portions by movement of said actuator; and an impervious washer in sealing engagement with an end of said porous element and including a bore connecting said porous element with one of said ports, said porous element including an outer side surface communicating with the other of said ports.

2. The apparatus defined in claim 1 wherein said actuator means includes a tip forming one of said shut-off valve portions and said housing means includes a bore forming the other of said shut-off valve portions.

3. The apparatus defined in claim 1 wherein said porous element is attached to said actuator means for longitudinal movement therewith, said outer side surface of said porous element slideably engaging the inner surface of a bore in said housing means.

4. The apparatus defined in claim 1 wherein said porous element is attached to an end of said actuator means and provided with a threaded outer wall in threaded engagement with a threaded bore in said housing means.

5. The apparatus defined in claim 1 wherein said porous element is attached to an end of said actuator means and provided with a threaded outer wall in threaded engagement with a threaded bore in said housing means and wherein one of said shut-off valve portions is formed by said end of said actuator means and the other of said shut-off valve portions is formed by a bore in said housing means.

6. A metering valve comprising, in combination, housing means forming a chamber including an inner wall surface, an inlet port and an outlet port; actuator means movably mounted in said housing and including an actuator wall surface; a porous element forming pas-

sage means connecting said two ports; an impervious washer in sealing engagement with an end of said porous element and including a bore connecting said porous element with one of said ports, said porous element including an outer side surface communicating with the other of said ports; a first shut-off valve portion on said actuator means; a second shut-off valve portion on said impervious washer, one of said valve portions being moveable through a flow metering range and into sealed engagement with the other of said valve portions by movement of said actuator means; and said actuator means including a portion provided with an impervious inner wall in sliding engagement with the outer wall of said porous element.

7. A metering valve comprising, in combination, housing means forming a chamber including an inner wall surface, an inlet port and an outlet port, actuator means moveably mounted in said housing and including an actuator wall surface; a porous element forming passage means connecting said two ports; an impervious washer in sealing engagement with an end of said porous element and including a bore connecting said porous element with one of said ports; said porous element including an outer side surface communicating with the other of said ports; a first shut-off valve portion on said actuator means; a second shut-off valve portion on said impervious washer, one of said valve portions being moveable through a flow metering range and into sealed engagement with the other of said valve portions by movement of said actuator means; said actuator means including a tip portion forming one of said shut-off valve portions and moveable into sealed surrounding relationship with the other of said shut-off valve portions formed by a portion of said impervious washer.

8. A metering valve comprising, in combination, housing means forming a chamber including an inner wall surface, an inlet port and an outlet port; actuator means moveably mounted in said housing and including an actuator wall surface; a porous element forming passage means connecting said two ports; an impervious washer in sealing engagement with an end of said porous element and including a bore connecting said porous element with one of said ports; said porous element including an outer side surface communicating with the other of said ports; a first shut-off valve portion on said actuator means; a second shut-off valve portion on said impervious washer, one of said valve portions being movable through a flow metering range and into sealed engagement with the other of said valve portions by movement of said actuator means; said actuator means including a tip portion provided with an impervious inner wall in sliding engagement with the outer wall of said porous element and wherein in said tip portion includes an annular end forming one of said shut-off valve portions and moveable into sealed surrounding relationship with the other of said shut-off valve portions formed by a portion of said impervious washer.
